UNITED STATES PATENT OFFICE.

WILLIAM HORROCKS, OF HERKIMER, NEW YORK.

TYPE-WRITER CABINET.

SPECIFICATION forming part of Letters Patent No. 503,418, dated August 15, 1893.

Application filed April 14, 1893. Serial No. 470,307. (No model.)

To all whom it may concern:

Be it known that I, WILLIAM HORROCKS, a citizen of the United States, residing at Herkimer, in the county of Herkimer and State of New York, have invented certain new and useful Improvements in Type-Writer Cabinets, of which the following is a specification.

My present invention relates to cabinets for type-writers, and the invention consists in a novel construction and arrangement of the movable parts, as hereinafter fully set forth.

Figure 1 is a perspective view of the cabinet opened, with the type-writer or machine shown in position for use, in dotted lines. Fig. 2 is a transverse vertical section, of the same, showing the parts in the same position. Fig. 3 is a similar sectional view showing the cabinet closed, and Fig. 4 is a top plan view of the movable base, for supporting and adjusting the machine, and showing the manner of mounting the same on the swinging shelf.

It is customary to so construct these cabinets that when the type writer is not in use the top of the cabinet will serve as a writing desk, and in order to move the type-writer into and out of position, to mount the same on a shelf that can be raised and lowered at will. The greatest difficulty with these cabinets as heretofore constructed has been to secure the necessary room or space for the knees of the operator below the swinging shelf when the latter is down, and the cabinet is being used as a desk, and in bringing the type-writer forward far enough to enable the operator to manipulate the machine without interference or obstruction by the sides of the cabinet which project above the shelf that supports the machine.

Heretofore it has been customary to so arrange the swinging shelf that as it is raised it will be moved forward to bring the machine to the required position. This forward movement is however necessarily limited, and that in turn compels locating the front edge of the swinging shelf very near the front edge of the cabinet, and that in turn limits the knee space underneath when the shelf is down. The object of my invention is to obviate both these difficulties.

In constructing my improved cabinet, I make the body A in the usual form as shown in Fig. 1, with a set of drawers on one or both sides of the central space, and then across this central space at the front I secure a fixed shelf or cross bar a, as shown in Figs. 1, 2 and 3, and to the rear edge of which I hinge the swinging shelf C, as shown in Figs. 2 and 3. To this shelf at one or both ends, I secure a segmental rack g, which engages with a corresponding rack h which is pivoted at c to the side of the case, and has an arm or extension L, to the outer end of which the cover or lid B is secured by a screw or pivot i, as shown in Figs. 2 and 3. At its outer end, this arm or lever L is widened, and this widened portion is provided with two inwardly projecting lips f and f', they being arranged at the proper angles for the cover B to bear against them—it resting against the lip f when the cover is raised as shown by the dotted lines in Fig. 3, and against the lip f' when the cover is closed, as shown in Fig. 3. The lip f' is not a necessity, but I prefer to use it as it serves to assist in supporting the cover when closed and thus relieves the screw or pivot i of the strain that would otherwise be thrown upon it. The cover B at its front has a strip e secured to it, of the proper width to fill the space between the cross bar a and the under side of the cover when the latter is closed, so as to bring its upper surface on a line with the top of the cabinet at each side, as shown in Fig. 3.

The shape and arrangement of the interlocking racks g h, and the lever L, are so proportioned, that when it is desired to elevate the type writer, it is only necessary to raise the front edge of cover B to the position shown by the dotted lines in Fig. 3, when striking against the lip f of lever L, the connection between the cover and the lever is thereby rendered rigid for the time being, when of course the further movement of the cover will carry with it the end of lever L, which being rigidly connected to the rack h will move it also, and that engaging with the rack g which is secured to the shelf C, will cause the latter with the machine to be thrown up to the horizontal position, while at the

same time the cover B will assume a vertical position as represented in Fig. 2, there being a pin or stop *b* to limit the movement of the parts and stop them when the shelf is at the proper position. I have also shown a similar stop *o* for the rack *g*, but it is obvious that both of these stops may be dispensed with by merely raising the cross piece *P* as represented in dotted lines Fig. 2 or by putting on it, located where shown, a strip or blocks of the proper thickness so that the back edge of the cover may rest thereon when in the vertical position. I prefer however to use at least the stop *b*, so as to leave the cover free to be moved without rubbing its back edge on the cross piece *P* in moving it as is necessary.

On the under side of the cover B I secure a strip or projections *t* to engage under the rear edge of the shelf C when raised, as shown in Fig. 2, and thus assist in supporting the rear edge of the shelf, a slight movement of the cover forward and back after the parts have been moved into position, serving to connect or disconnect them.

If desired, a spring may be applied to press the cover up against the rear edge of the shelf, or a catch or fastening of any kind may be used; or, the part *t* may be of metal with a cavity in its top in which a small spur or projection secured to the shelf may engage. As however, when the machine is raised and moved forward as hereinafter explained, the weight of the cover and of the lever *L* will fully counterbalance the shelf and the machine, there will be little or no tendency of the shelf to swing or drop down. In this connection I would remark, that the rear end of the lever *L* may be increased in weight to any extent desired by simply widening it, (it being made of cast iron) and thus be made to act as a counterbalance in connection with the cover, to the weight of the machine and its hinged shelf C. By this means I dispense with the weight and pulleys heretofore used in these cabinets.

In order to enable the type-writer to be moved forward to the required position after the shelf C has been raised, I provide a separate base piece I, which may be a simple piece 50 of wood or board of the proper size, for the machine to rest on, and place it on the shelf C loosely, it being held in place on the shelf by light metallic clips *l* and *l'*, as shown in Fig. 4, or by any equivalent means, such as 55 slots and screws, as indicated by dotted lines in Fig. 4, the slots being cut in the base piece I or in the shelf C as may be preferred. I prefer however, to use the metal clips, as shown; and to hold the base with the machine from accidental movement, I secure to one of the clips a spring *r*, having curved ends which engage in notches *m* in the edge of the base plate, as shown clearly in Fig. 4, there being a series of these notches so that 60 the machine may be adjusted at any point desired, forward or back.

Any equivalent means may be used for locking the base plate and machine in position, or they may be dispensed with entirely, as the machine being secured to the base plate 70 I and the latter being held by the clips or equivalent means, will have little or no tendency to move when the machine is being used, but I prefer to use the spring as shown, it being both simple and efficient. By this 75 arrangement, it will be seen that after the shelf has been raised to the horizontal position as in Fig. 2, the machine may be drawn forward as far as may be desired, and until it rests upon or over the solid cross bar *a*, and 80 may be made to project beyond the front of the cabinet to a much greater extent than is possible with the swinging shelves heretofore used. This arrangement also enables me to make 85 the knee space under the shelf ample, as the cross bar *a* may be made much wider than shown, thereby throwing the top of the shelf that much farther back, and correspondingly increasing the depth of this space from the front backward, the only limit in that respect 90 being that there shall be sufficient room for the machine when the shelf is lowered and the lid B is closed or shut down. In case the spring *r* or other fastening be not used to hold the machine in place on the shelf C, 95 then there should be a stop *v* secured to the shelf as shown in Figs. 2 and 3 for the end of the base plate to rest against when the shelf is lowered, so as to prevent the machine from sliding down against the back of the cabinet. 100

When it is desired to close the cabinet it is only necessary to first shove the machine back on the shelf C, then take hold of the top of the lid B, give it a slight backward movement to disconnect it from the shelf and draw it 105 upward and forward, which movement by means of the lever *L* and the racks *g* *h* will cause the shelf to swing down to the position shown in Fig. 3, the lid B being brought down flush with the top at the sides. 110

Having thus fully described my invention, what I claim is—

1. The combination in a cabinet, of the shelf C having its front edge hinged to the cross bar or shelf *a* and provided with the segmental rack *g*, the pivoted lever *L* provided at one end with a segmental rack *h* arranged to engage with said rack *g*, and the lid B, pivoted to the opposite end of the lever *L*, substantially as shown and described. 115

2. The combination in a type writer cabinet of a hinged shelf C arranged to have its rear edge swing upward, and a lid B arranged to swing downward in rear of said shelf, and having a projection *t* thereon arranged to engage under the rear edge of the shelf and support it when raised, substantially as shown and described. 120

3. The combination in a type-writer cabinet, of the swinging platform C hinged at its front edge to the cross bar *a*, and the sliding plate or base board I, with the metal clips *l* and 125

l', said plate or base board being arranged to slide forward and rest upon the fixed cross bar, substantially as shown and described.

4. In combination with the platform C, the 5 sliding plate or base board I provided with notches *m*, and the clip *l* with the curved spring *r* arranged to engage in said notches substantially as and for the purpose set forth.

In witness whereof I hereunto set my hand in the presence of two witnesses.

WILLIAM HORROCKS.
